UNITED STATES PATENT OFFICE.

WILLIAM A. HEMENWAY AND ORA E. HEMENWAY, OF COTTAGE GROVE, OREGON.

FLY-CATCHER.

1,190,165.

Specification of Letters Patent.

Patented July 4, 1916.

Application filed March 7, 1916. Serial No. 82,603.

To all whom it may concern:

Be it known that we, WILLIAM A. HEMENWAY and ORA E. HEMENWAY, citizens of the United States, residing at Cottage Grove, 5 in the county of Lane, State of Oregon, have invented a new and useful Fly-Catcher; and we do hereby declare the following to be a full, clear, and exact description of the invention, such as will enable others skilled in 10 the art to which it appertains to make and use the same.

This invention relates to an improved fly catcher, and an object of the invention is to provide a device of this kind comprising 15 a holder for sticky fly paper, for catching flies, which alight on the ceiling or side wall.

Another object of the invention is to provide a fly catcher, which involves the same principle, as set forth, shown and claimed 20 in the patent to William A. Hemenway and Ora E. Hemenway, Sept. 21, 1915, Patent No. 1,154,810, in so far as providing means to receive and hold a piece of sticky fly paper. In the above patent great difficulty 25 has been experienced in using the fly catcher in said patent for sweeping and scraping the flies off the ceiling and side wall, for instance the flies fall adjacent the edge of the sticky fly paper, that is, without sticky 30 or adhesive material, therefore escaping. In the present device this disadvantage is materially avoided or obviated. For instance, the holder is so constructed, that it may be held or disposed on an angle as shown in the 35 drawings, whereby the uppermost edge of the holder may contact with the ceiling or side wall in a sweeping motion, so as to disturb the flies, which will fly toward the sticky paper and alight thereon and be 40 caught. After one side of the paper is filled, the holder may be tilted upon an opposite angle and moved over the surface of the ceiling or side wall, so that the other half of the paper may be filled.

45 Another object of the invention is to otherwise improve, simplify and render more efficient and practical, the construction of fly catcher set forth in said patent.

In practical fields the details of construction 50 may necessitate alterations, falling within the scope of what is claimed.

The invention comprises further features and combination of parts, as hereinafter set forth, shown in the drawings and claimed.

55 In the drawings: Figure 1 is a view in perspective, showing the holder disposed on

an angle when sweeping the ceiling or side wall in one direction. Fig. 2 is a view in side elevation, showing the holder tilted upon an opposite angle to that in Fig. 1 in 60 sweeping the ceiling or side wall in an opposite direction. Fig. 3 is a sectional view transversely on line 3—3 of Fig. 2.

Referring more especially to the drawings, 1 designates a plate constructed of any 65 suitable sheet metal, preferably tin, and which may be any suitable size and shape. However, in the present case this plate is of an elongated rectangular contour having its opposite longitudinal side portions bent 70 upon themselves to form the flanges 3, which overlie the face of the plate and spaced apart therefrom, to provide guides 4, to receive a sheet of sticky fly paper, which may be inserted in said guide from either end of the 75 plate. These flanges are re-bent, as shown at 6, to provide laterally extending additional flanges 7, which constitute guard means, to prevent the flies from escaping, or falling beyond the plate, and insuring 80 that they will strike or alight on the sticky part of the paper. Adjacent each end of the plate a tang is struck up, and after inserting the fly paper in the guide the tang may be bent toward the plate and in contact 85 with the fly paper to hold the same secure. The opposite end edge portions are bent upon themselves, thereby forming strengthening ribs 9 for the plate, as well as strengthening and reinforcing the tangs 10, where 90 they are struck up from the plate. The opposite face of the plate of the holder is provided with a pair of laterally extending ears 11, between which upon a pin 12, a socket member 13 is pivoted, there being a thumb 95 nut, to hold the socket member in different adjusted positions, whereby the holder for the sticky fly paper may be held at different angles relative to the ceiling or side wall. A handle 14 is designed to engage the 100 socket member, to support the holder in the desired manner, whereby it may be swept across the ceiling or side wall in angular position, so that the flies in leaving the surface of the ceiling or side wall will alight 105 upon the sticky fly paper, and therefore become caught.

The invention having been set forth, what is claimed as new and useful is:

In a fly catcher, a holder for sticky fly 110 paper comprising a plate having its longitudinal side portions bent upon themselves

2

to form overlying flanges, thereby providing longitudinal oppositely disposed grooves between the flanges and the plate for the reception of a sheet of sticky fly paper, said flanges being rebent to form laterally extending additional flanges, constituting guards to prevent the flies from escaping or falling beyond the plate, said additional flanges having their extreme end portions bent upon themselves to reinforce the flanges, the ends of the plate having struck-up lugs or tongues to be bent over the ends of the fly paper, the ends of the plate being

bent upon themselves forming ribs or thickened parts, to reinforce the plate, and a pivotal adjustable handle socket secured centrally to the under face of the plate.

In testimony whereof we have signed our names to this specification in the presence of two subscribing witnesses.

WILLIAM A. HEMENWAY.
ORA E. HEMENWAY.
